UNITED STATES PATENT OFFICE.

WILLIAM M. DUNCAN, OF ALTON, ILLINOIS.

FURNACE-GRAVE.

1,132,918.

Specification of Letters Patent. Patented Mar. 23, 1915.

Application filed February 21, 1913. Serial No. 749,804.

To all whom it may concern:

Be it known that I, WILLIAM M. DUNCAN, a citizen of the United States of America, and resident of Alton, in the county of Madison and State of Illinois, have invented certain new and useful Improvements in Furnace-Grates, of which the following is a full, clear, and exact description, reference being had to the accompanying drawings, forming a part of this specification.

My invention relates to a furnace grate and has for its object the production of a grate structure including traveling fuel carriers closely fitted to each other to prevent fine particles of fuel from falling through the grate, combined with means for forcing air directly into the fuel overlying said closely fitted traveling carriers.

Another object is to produce a grate having fuel carriers serviceable also as ash conveyers, operable to carry fuel toward the rear of the grate, and thereafter convey the ashes to the front of the grate structure. These combined fuel carriers and ash conveyers are preferably in the form of buckets hinged to a traveling sprocket chain and adapted to tilt at the rear end of the grate so that each bucket will automatically discharge a quantity of ashes into the next preceding bucket. The buckets therefore serve as receptacles for receiving the ashes, and for conveying them forwardly until they are again tilted to discharge their contents.

Figure I is a side elevation, partly in section, of a grate structure embodying the features of my invention. Fig. II is an enlarged transverse section, taken approximately on line II-II, Fig. I. Fig. III is a perspective view of one of the grate bars or buckets of my grate.

In the accompanying drawings:—1 designates side frames mounted on wheels 2, and serving to support the various elements forming my grate structure.

3 designates a drive shaft provided with drive wheels 4, and 5 is an idle shaft provided with plain wheels 6. Endless sprocket chains, operable around the wheels 4 and 6, are composed of links 7 connected by hinge pins 8, each of said hinge pins being provided with a roller 9 which travels along a track 10. A combined fuel carrier, or grate bar, and ash conveyer, in the form of a bucket A is hinged to each hinge pin 8, said

bucket being provided with side wings 11, through which the hinge pin passes. These buckets A are preferably formed with flat walls 12, which support the fuel and provide a substantially flat grate surface. To permit close assemblage of the buckets and prevent fuel from dropping through the traveling grate, each bucket A is offset at 13 to receive the lip 12' of the bucket directly in front of it. The hinged buckets are also provided with abutment lugs 14, adapted to rest upon the top faces of the adjacent chain links 7, the function of these abutment lugs being to limit the swinging movement of the buckets, thereby maintaining the buckets in predetermined positions while they are serving as grate bars.

One of the important features of this invention lies in the buckets A being closely fitted to each other so as to retain the fine particles of fuel within the fuel bed. This is important, for the reason that fine coal, commonly called slack, which is inexpensive, will burn readily on a traveling grate. However, as the air necessary for combustion cannot pass through the closely fitted grate bars of the buckets A, some means must be provided for introducing air into the fuel at points above said buckets. I, therefore, arrange air boxes 15 between the buckets A, said air boxes being supported partly by transverse rods 16 and partly by a manifold 17. The manifold has flanged ends that are secured to the side frames 1. Each air box 15 is secured to the manifold and provided with an opening 18 which registers with a corresponding opening in the manifold. Air under pressure may be conducted to the manifold through a supply pipe 19, and, after passing into the air boxes, is discharged through perforations 20 in the top and sides of the air boxes above the traveling grate members. It will be noted that the air boxes are closed to prevent the escape of air through their side and bottom walls, and that the discharge perforations 20 are located in a higher plane than the top faces of the buckets A; hence the air is forcibly discharged directly into the fuel.

21 designates scrapers arranged in the air boxes for the removal of ashes that may become deposited therein.

In the practical use of my invention, the fuel is fed onto the grate at B, (Fig. I),

and carried in the direction of the arrow 22 to the rear end of the grate. Combustion takes place while the fuel is moving toward the rear of the grate and, as the hinged buckets of the traveling grate pass around the idle wheel 6, the buckets swing by gravity about the axis of the hinge pins 8 so as to discharge the ashes from the top faces of the buckets. It will be noted that the 10 swinging movement of the buckets is limited at this time by a curved runway plate 23, and that each bucket is positioned to receive the ashes discharged from the next succeeding bucket. The ashes are jarred from the 15 buckets when the latter strike curved runway plate 23 and this plate confines the ashes at the discharge point so that they will be positively transferred from the grate bar surface of one bucket to the interior of the next preceding bucket. The buckets 20 then serving as ash conveyers, travel along the runway plate 23, pass over rollers 24 and intermediate runway plates 23', and at a point near the front end of the grate 25 structure, the buckets are temporarily prevented from tilting by a plate 25. After passing over the plate 25, the buckets are free to tilt, with the result of discharging their contents, all of the ashes being dis-

charged at an accessible point at which they 30 may be removed.

I claim:

A furnace grate comprising endless sprocket chains, buckets hinged to said chains and freely tiltable relative to the 35 chain links, a front support and a rear support about which said chains travel in a continuous circuit, providing for the movement of the chains and buckets in an upper course and in a lower course, an abutment 40 at the rear of the grate against which said buckets strike in tilting automatically at the rear end of the grate while passing from their upper course of movement to their lower course of movement, whereby ashes 45 resting upon the buckets are jarred therefrom and caused to be deposited into the preceding tilted buckets, and a runway on which said buckets are moved toward the links of said chains and held approximately 50 parallel therewith while traveling through the lower course toward the forward end of the grate.

W. M. DUNCAN.
